UNITED STATES PATENT OFFICE

20,485

BOLT

John A. MacLean, Chicago, Ill., assignor to MacLean-Fogg Lock Nut Company, Chicago, Ill., a corporation of Illinois

Original No. 1,946,800, dated February 13, 1934,
Serial No. 499,561, December 2, 1930. Application for reissue February 7, 1936, Serial No. 62,780

4 Claims.

(Cl. 85—9)

The present invention relates to bolts, and is particularly concerned with improvements in water-tight bolts for use in railway freight and passenger cars and industrial cars and the like.

5 While the present invention is of particular importance in connection with railway freight cars, it should be understood that the present bolt is capable of universal use and will be found advantageous wherever it is desirable to effect a 10 waterproof or water-tight seal about the head of the bolt, or where it is desirable to utilize any of the other novel features of the bolt.

The railway freight cars of the prior art, which have their wooden sheathing secured by ordinary 15 bolts, such as carriage bolts, are subject to the disadvantage that the wooden sheathing must be countersunk to receive the heads of the carriage bolts. In countersinking for the heads of the bolts, the edges around the countersunk holes are 20 nearly always ragged and splintered. These ragged and splintered edges are the cause of loss and damage to lading contained in sacks, such as flour, sugar, cement, etc. It is, therefore, a desideratum in freight cars, that all fastening devices 25 for sheathing, floors and any other portion of cars where bolts extend from inside to outside of cars, be installed with the heads flush with the surface of the wood. It also should be borne in mind that countersinking of the wood cuts a 30 great deal of it away, thus materially decreasing its strength.

Another disadvantage of the prior art bolts is that water leaks in past the heads of the bolts so that the lumber soon begins to rot beneath the 35 bolt head. The sheathing becomes loose, holes are formed in the sides and floors of the car, permitting leakage of the cargo such as grain, etc. The water which leaks past the bolt heads often causes damage to the cargo.

40 One of the objects of the present invention is the provision of an improved water-tight bolt of the same general type covered by my prior application, Serial No. 423,011, filed January 24, 1930.

Another object of the invention is the provision 45 of an improved car construction including water-tight fastening devices for sheathing, flooring, roofing and other portions of cars where bolts extend from inside to outside, for the purpose of eliminating looseness and rotting of the lumber 50 about the bolts.

Another object is the provision of an improved bolt having a head adapted to be drawn into sealing engagement with the lumber, so as to eliminate the difficulties brought about by leakage of 55 water past the head of the bolt.

Another object is the provision of a bolt of the class described, in which the head is adapted to be drawn substantially flush with the wood surface, thus eliminating the operation of countersinking, which is necessary with carriage and other types of sheathing or flooring bolts, and to aid in effecting a waterproof seal about the head of the bolt. 5

Another object is the provision of a bolt for use in coal mine pit and conveying cars and the like. Cars of this class are fastened with carriage 10 bolts, the heads of which project inside of the cars. In dumping the load, a great deal of coal is crushed and broken up by these carriage head bolts. This degrades the coal. With the use of the improved bolt, the inside surfaces of the cars 15 would be smooth, thus eliminating breakage and degrading.

A further object of the invention is the provision of an improved wood bolt provided with a head having portions adapted to be drawn into 20 the wood to form a fluid-tight seal, and also to prevent the bolt from turning.

A further object of the invention is the provision of an improved wood bolt provided with a head having, on its underside, a ridge around the 25 shank, which is out of circular relation with respect to the center of the shank.

A further object of the invention is to provide a bolt with an improved shoulder on the shank 30 adjacent the head.

A further object of the invention is to provide a bolt having an improved shoulder on the shank adjacent the head, and having a ridge on the underside of the head in such relation that the shoulder and ridge cooperate to ensure intertight 35 seal between the head and wood to which the bolt is applied.

Other objects and advantages of the invention will be apparent from the following description and from the accompanying drawings in which 40 similar characters of reference indicate similar parts throughout the several views, and in which:

Figure 1 is a sectional view taken through a part of the railway car, showing wooden flooring 45 or sheathing secured with a bolt constructed according to the present invention.

Fig. 2 is a sectional view of the bolt, taken on the plane of the line 2—2 of Fig. 1.

Fig. 3 is a similar view of a modified form of 50 bolt.

Fig. 4 is a similar view of a modified form of bolt.

Fig. 5 is a similar view of a modified form of bolt. 55

ample, is shown as of hexagonal configuration. As will be seen from Fig. 8 the shoulder 24 tapers inwardly away from the head 17 so that, when the bolt is driven into the wood, the sloping sides 5 displace the wood in the radial direction and makes a very tight seal.

It will be understood that I do not intend to be limited to a tapered shoulder of any particular cross section, since tapered shoulders of any cross 10 section exert a beneficial camming action. In Figs. 10 and 11, I show a bolt having a tapered shoulder 25 of square cross section, and by way of example, a square ridge 22 arranged so that the sides of the shoulder and the inner sides of 15 the ridge compress the wood between them.

In Figs. 12 and 13, I have shown a bolt having a tapered shoulder 26 of round cross section. By way of example, the head may not be provided with a ridge, although a ridge of any configuration 20 may be provided on the underside of the head 17, if desired. The shoulder 26, being frusto-conical in shape, exerts considerable pressure on the adjacent wood without fracturing the fibers, and consequently serves to a great extent 25 to maintain a watertight seal around the bolt.

The operation and installation of the present bolt is as follows:

The lumber 10 is preferably provided with a bore 14 slightly smaller than the body 18 of the 30 bolt, to provide a close fit, and the bolt 11 may be driven into the bore as far as possible with a hammer or other driving tool. The nut 15 may then be placed upon the threaded portion 16 of the bolt, and the nut threaded home by means 35 of a wrench or other tool, during which operation the bolt will be gradually drawn into the bore 14, the head embedding itself in the surface of the lumber about the bore 14, until the head is substantially flush with the surface of the lumber. During this operation, the ridge 22 is drawn 40 into the lumber, and since it is located in non-circular relation to the shank, rotation of the bolt is prevented.

The ridge 22 compresses the fibers of the lumber, and since such ridge is in the form of a continuous figure, a zone of compressed fibers is provided around the shank, thereby insuring a substantially perfect waterproof seal. Where the bolt is provided with a shoulder of the type shown 50 or an equivalent shoulder, the shoulder displaces part of the wood outwardly towards the ridge 22, increasing the sealing pressure acting on the wood and providing a superior seal.

The nut 15 and thread 16 constitute a force 55 multiplying device for effecting the sealing engagement between the head and the lumber, as well as means for permanently securing these parts in sealing engagement, and any kind of nut, including lock nuts or lock washers, may be 60 employed for this purpose.

It will thus be observed that I have invented an improved bolt, which has peculiar advantages when used in connection with refrigerator cars, for the reason that it is highly desirable to avoid 65 leakage of water into the holes about the bolts in such cars. The present bolts effect a substantial improvement in the life and serviceability of the cars which are equipped with such bolts, and the bolts are adapted to prevent leakage and 70 enable the lumber to give good service for a much longer period of time than the devices of the prior art. When the present bolts are employed with relatively hard wood, the heads of the bolt provide a perfectly waterproof seal, which 75 prevents water from leaking through the floor.

damaging the installation and rotting the lumber.

It is of the utmost importance that the insulation of refrigerator cars be kept dry in order to maintain the insulating value, and particularly 5 on account of the fact that the insulation is enclosed between the walls of the car where it will not dry out very quickly, should it ever become wet.

While I have illustrated preferred embodiments 10 of my invention, many modifications may be made without departing from the spirit of the invention, and I do not wish to be limited to the precise details of construction set forth, but desire to avail myself of all changes within the 15 scope of the appended claims.

Having thus described my invention, what I claim as new and desire to secure by Letters Patent of the United States, is:

1. An article of manufacture, comprising a 20 replacement bolt for wood holes comprising a bolt shank having a head, force multiplying means carried by the end of said shank for drawing the head into engagement with the wood of a member secured by said bolt, said shank having a non-circular tapered portion adjacent said head, and having wedging surfaces, said tapered portion of the shank increasing in size from the shank to the head and being adapted to be wedged into a worn wood hole to contact the wood fibers 30 surrounding the upper end of the hole, said head comprising a circular member tapering gradually from its center toward its outer edges and adapted to be drawn into the wood substantially flush with the upper surface thereof, and a non-circular ridge having its sides parallel to the 35 said wedging surfaces, substantially V-shaped in cross-section, carried by the lower side of the head for effecting a water-tight seal between the head of the bolt and the adjacent wood, said ridge being adapted to prevent rotation of the bolt and cooperating with the wedging surfaces to cam the intermediate wood fibers when being drawn up.

2. An article of manufacture comprising a 45 water-tight bolt for wood comprising a bolt shank having a head, force multiplying means carried by the end of said shank for drawing the head into engagement with the wood of a member secured by said bolt, said shank having an elongated tapered portion adjacent said head, said tapered portion of the shank increasing in size from the shank to the head and being adapted 50 to be wedged into a hole in the wood to compress the wood fibers surrounding that end of the hole, said head comprising a member adapted to be drawn into the wood substantially flush with the outer surface of the wood, and having a non-circular ridge on its lower side, said ridge being substantially V-shaped in section and adapted 55 to cooperate with said tapered portion on said shank to effect a water-tight seal between the head of the bolt and the adjacent wood.

3. An article of manufacture comprising a 65 water-tight bolt for wood comprising a bolt shank having a head, force multiplying means carried by the end of said shank for drawing the head into engagement with the wood of a member secured by said bolt, said shank having an elongated tapered portion adjacent said head, said 70 tapered portion of the shank increasing in size from the shank to the head and being adapted to be wedged into a hole in the wood to compress the wood fibers surrounding that end of the hole, said head comprising a member adapted 75

to be drawn into the wood substantially flush with the outer surface of the wood, and having a ridge on its lower side, said ridge being substantially V-shaped in section and adapted to cooperate with said tapered surface on said shank to effect a water-tight seal between the head of the bolt and the adjacent wood, said ridge being non-circular in plan and adapted to prevent rotation of the bolt when the bolt is being drawn into engagement with the wood.

10 4. A bolt for the purpose described, having a threaded cylindrical body and a head on which

is a downwardly extending flange terminating in a cutting edge, said bolt being provided adjacent its head with a non-circular part projecting beyond the body and extending below said flange, the under surface of said head being tapered to provide an inclined face extending from said flange to the non-circular part and opposing the inner wall of said flange to compress the material to which the bolt is applied and thereby form a water-tight joint.
